UNITED STATES PATENT OFFICE.

HENRY WILVERTH, OF ST. CHARLES, KENTUCKY.

MINING-MACHINE.

SPECIFICATION forming part of Letters Patent No. 289,742, dated December 4, 1883.

Application filed October 16, 1882. (No model.)

To all whom it may concern:

Be it known that I, HENRY WILVERTH, of St. Charles, in the county of Hopkins and State of Kentucky, have invented a new and 5 useful Improvement in Coal-Excavators, which improvement is fully set forth in the following specification and accompanying drawings, in which—

Figure 1 is a perspective elevation of the 10 improved coal-excavator. Fig. 2 is a top view of the swinging beam which carries the excavating-bit, and Fig. 3 is a vertical longitudinal section of the joint or pivot for the swinging beam.

15 The object of my invention is to provide a new and improved coal-excavator; and it consists of a tubular standard on a suitable base, having at its upper end a head screw-threaded within to receive a screw-threaded rod, so that 20 when the standard is placed in the channel of a mine the screw-rod performs the office of a jack and holds the standard firmly between the floor and roof of the channel. The standard is further provided with a crane, which is 25 capable of swinging around from side to side. A balanced lever having at one end a handle and at the opposite end the excavating-bit is attached to the end of the crane by a chain and balanced, all of which will now be described in detail.

In the accompanying drawings, A represents a suitable base composed of a cross-piece of any convenient size or shape.

B is a tubular standard, preferably made of 35 gas-pipe, secured permanently to the base-piece A. The upper end of the standard has a head, C, screwed thereon. The head has a screw-threaded aperture to receive a screw-threaded shaft or rod, D, provided with a 40 swivel-head, E. The rod D has also holes F at the upper end, to enable a small hand lever or rod to be placed therein for the purpose of manipulating the screw. The body of the tubular standard B has a series of holes, G, 45 in one side, as shown. The standard carries an arm or crane, H, which arm is pivoted on the standard by suitable bearings, I. One of these bearings is provided with a thumb-nut, J, so that when the crane has been rotated to 50 any point the thumb-nut will hold it in position. Pins placed in the holes G serve to hold

the crane after being vertically adjusted. The outer end of the crane is provided with an eye, K, to which is attached the pendent chain L.

The beam M, which carries the excavating-bit, is made of any suitable size and length, and is provided at the forward end with a socket or eye, to which the bit N may be attached. At a point near the center is a rib or shoulder, O, and a thimble or globular 55 coupler, P, is placed on this beam loosely, so that one side rests against the shoulder O. A pin, Q, through the beam serves to hold the coupler in position. The coupler is provided with two lugs or studs, R, which project out 60 on opposite sides at right angles to the line of the beam. A loop, S, having a hook, is secured to these projecting lugs R, and the hook T is attached to the pendent chain, so that the beam is carried thereby. A weight, U, is 65 placed on the rear end of the beam, to counterbalance the forward end of the beam. At the extreme rear end of the beam is an arm, V, projecting upward at right angles from the beam M. This arm is adjustable by means of 70 the bolt V', as shown.

W represents a bar having its forward end forked and attached to the lugs or studs R, projecting from the coupler P. Its rear end is attached to the arm V, and carries also a 80 cross-handle, X, by means of which the operator manipulates the beam. A handle, Y, is also placed on the bar W at a suitable point between the arm V and the coupler P.

It will be observed that in operation the 85 beam is counterbalanced by the weight U, and is capable of being turned or revolved in the coupler P, when the set-screw or bolt V' is released, thus enabling the operator to incline the prongs of the forked bit N in any direction. It is also obvious that when the beam is thus suspended on the crane H the bit may 90 be directed to any point by means of the handles X Y, and propelled forward with great force against the mass of coal.

95 The operation is as follows: The base and standard are placed in the channel at a suitable point, and the jack-screw at the upper end employed to hold the same firmly between the floor and wall. The crane H is then turned 100 to the proper position to permit the swinging beam to work freely and not obstructively.

The operator then grasps the handles X Y, and, drawing back the same, propels the beam forward in the direction required. The weight of the beam, the counter-balance U, and the globe-coupling P all serve to furnish momentum in the operation.

What I claim is—

1. In coal-excavators, the rotatable beam M, having centrally the globe-connection P, and at the rear end the adjustable arm, in combination with the bar W, hinged at its forward end to the globe-coupling, and attached at its rear end to the arm V, and with the crane H, to which it is suspended by the chain L, substantially as and for the purpose set forth.

2. The base A and tubular standard B, having at its upper end the jack-screw and the rotating crane H, as shown, in combination with the rotatable beam M, having the globular coupling P, counter-weight U, and adjustable arm V, and with the forked bar W, handles X Y, and loop S, hook T, and supporting-chain L, substantially as herein set forth.

In testimony that I claim the foregoing I have hereunto set my hand, this 2d day of 25 October, 1882, in the presence of witnesses.

HENRY WILVERTH.
